JOHN O'CONNOR, OF NEW YORK, N. Y., ASSIGNOR OF ONE-HALF TO TYRONE REALTY IMPROVEMENT COMPANY, OF NEW YORK, N. Y., A CORPORATION OF NEW YORK.

MUSIC-LEAF TURNER.

No. 858,204.

Specification of Letters Patent.

Patented June 25, 1907.

Application filed November 1, 1905. Serial No. 285,502.

To all whom it may concern:

Be it known that I, JOHN O'CONNOR, a citizen of the United States, and a resident of the city of New York, borough of Manhattan, 5 in the county and State of New York, have invented a new and Improved Music-Leaf Turner, of which the following is a full, clear, and exact description.

This invention relates to improvements in 10 music leaf turners, the object being to provide a device of this character that will be simple in construction and designed to be attached to a piano or similar instrument, or to a music rack, and adapted to be operated by 15 foot pressure, thus leaving the hands of the player free at all times to operate the musical instrument, the parts being so arranged that the music leaves may be quickly turned one at a time as the music progresses, or simultaneously turned back to a closed position.

Other objects of the invention will appear in the general description.

I will describe a music leaf turner embodying my invention and then point out the 25 novel features in the appended claims.

Reference is to be had to the accompanying drawings forming a part of this specification, in which similar characters of reference indicate corresponding parts in all the figures.

Figure 1 is a front elevation of a piano with a leaf turner embodying my invention, thereon; Fig. 2 is a plan partly in section, of the turner mechanism; Figs. 3 and 4 are detail plans showing the turning mechanism in different positions; Fig. 5 is a sectional elevation with parts removed; Fig. 6 is a section on the line 6—6 of Fig. 2; Fig. 7 is a detail plan showing the turning arms employed; Fig. 8 shows in perspective a covering plate and means for holding a music sheet; Fig. 9 shows one form of sheet holder employed; Fig. 10 shows another form of sheet holder. Fig. 11 indicates the pneumatics employed; Fig. 12 illustrates a portion of a back support for the music sheet. Fig. 13 is a sectional detail showing another portion of the back support; Fig. 14 shows a joint connection between members of said support; Fig. 15 illustrates another connection thereof.

Referring to the drawings, 10 designates a base or support which is chambered as indicated at 11, to receive certain working parts

of the music leaf turner the center portion of the chamber extending through the base. 55 Arranged in the base are inner and outer segmental walls 12, 13 of suitable metal, and extended from the plate 14 to which the walls 12 and 13 are attached is a wall formed in the arc of the circle, the upper edge of which 60 forms a track 15, the said track being arranged between the walls 12 and 13 and inclined downward from its connection with the plate 14. The plate 14 has a portion 16 extended underneath the base 10 on which 65 parts 12, 13 and 15 are supported, and extending upward from this portion 16 is a post 17 on which is mounted to turn, a plurality of leaves carrying arms 18, and on the free ends of these arms 18 are devices for engaging with 70 the music sheets. The first arm of the series has sheet engaging devices consisting of two wires 19; the other arms however, are each provided with a single wire 20 designed to engage with the inner side of a leaf, while the 75 outer side at the bottom is engaged by a spring clip 21. These leaf engaging devices are pivotally connected to the arms 18 so that when the device is not in use it may be folded down closely upon the base. The 80 several arms 18 are arranged one upon the other as clearly shown in Fig. 6 and are placed between a sleeve 22 and a washer 23 on the post 17. Mounted to swing on the sleeve 22 are turning arms 24, there being one turning 85 arm for each arm 18; these turning arms 24 are placed one above the other and are held yieldingly together and upon the incline 15, by means of a spring 25 surrounding the sleeve 22 and engaging with the uppermost 90 arm 24. Each turning arm 24 is provided at its free end with a notch 26 for receiving a finger 27 extended downward from the free end of the arm 18 co-acting therewith; the several turning arms or leaf carrying arms 95 engaging therewith are held by a detent plate 28 mounted to swing on a shaft 29, having bearings in a bracket 30 attached to the plate 14. Rigidly attached to the end of the shaft 29 is a detent 31 which will prevent the plate 28 from moving too far downward; it is however held yieldingly downward or moved to its downward position by means of a coiled spring 32 surrounding the shaft and having one end connected to the plate 28 and the 105 other end connected to an arm of the detent

31. The end of the shaft 29 opposite that to which the detent 31 is connected is curved outward and then forward as indicated at 33; this portion 33 extends underneath the several arms 24 and engaging with the lowermost one thereof. The portion 33 of the shaft is held yielding downward by means of a spring 34 surrounding the shaft 29 and connected with one end to the cranked portion 10 of the shaft and at the other end to the bracket 30 as clearly illustrated in Fig. 4.

Mounted to rotate on the post 17 is a pinion 35, extended outward from which is a shifting arm 36 and yieldingly mounted on this 15 shifting arm 36 is an upwardly extended finger 37; this finger 37 as here shown is attached to a shaft 38 mounted to turn in the arm 36, and held yieldingly in one position by means of a coiled spring 39 which surrounds the 20 shaft, one end of the spring being connected to the shaft while the other end is connected to the arm 36. The shaft carrying the finger 37 is designed to rotate in one direction only, during its operation, and to prevent its movement 25 in the opposite direction, when shifting the arms 24 as will be hereinafter described, the inner end of the shaft 38 is turned outward as indicated at 40, to engage against the inner side of the shifting arm 36. It will 30 be noted in Fig. 3 that the said shifting arm is provided with a slot in which the shaft and spring are arranged. A boss or cam 41 is formed on the free end of the shifting arm 36 and is designed to rock the shaft 29 as will 35 be hereinafter described. Engaging with the pinion 35 is a rack 42 from which a rod 43 extends to connection with a piston operating in a cylinder 44, and communicating with the interior of the cylinder 44 at the 40 outer end is a pipe 45 which is connected by a flexible tubing 46 with a pipe 47 leading into the lower end of a pneumatic consisting of a cylinder 48 within which is a piston having a stem 49 projected through the top of 45 the cylinder and terminating in a foot-plate 50; between this foot-plate 50 and the top of the cylinder 48 is a spring 51 for moving the piston upward. This pneumatic 48 is arranged in a base frame 52 as is also another 50 pneumatic to be described, and this base plate is secured near the foot pedals of the musical instrument, so that the pneumatic may be operated by a person's foot. Also mounted on the post 17 is a pinion 53 on 55 which is rigidly secured a returning arm 54 having an upwardly extended finger 55, and this pinion 53 is engaged by a rack 56 having a rod connection 57 with a piston 58 operating in a cylinder 59, and between the piston 58 and the inner end of the cylinder 59 is a spring 60 for moving the piston in one direction. It may be here stated that the piston in the cylinder 44 is moved in one direction by means of a similar spring. Communicating 60 with the interior of the cylinder 59 is a

tube 61 which has a flexible tube connection 62 with a pipe 63 leading into the lower end of a pneumatic cylinder 64 having a piston 65 the stem of which extends upward through an opening in the top of the cylinder and is 70 provided with a foot-plate 66 between which and the top of the cylinder is a spring 67 for moving the piston upward.

When the parts are assembled in the base 10 which has an opening at its top, the walls 75 12, 13 and the parts contained within the circumference thereof are covered by a segmental plate 68 which at its rear side is provided with a wire 69 for engaging between the center leaves of the music sheets at the front. 80 This wire 69 is designed to be turned downward for convenience in placing the music on the device and it is held yieldingly upward by means of a plate spring 70 attached to the inner side of the plate 68, and engaging with 85 an outwardly turned finger 71 on a horizontally disposed portion 72 of said wire 69. This horizontally disposed portion 72 being arranged to turn in a suitable bearing attached to the under side of the plate. The 90 music sheets are supported at the rear side by a standard consisting of folding sections 73, 74, the section 73 being pivotally connected to the plate 14 or to an upward extension 75 thereon and it is held in its upright position 95 by means of a lug 76 on the lower end of the section 73 engaging in a depression or hole in the plate 14, it being understood that the section 73 of the standard has sufficient resilience to permit the said lug to be moved 100 into or out of the depression or hole in the plate. The section 74 of the standard below its pivotal connection with the section 73 is also provided with a lug 77 for engaging in a hole 78 formed in the section 73, thus holding 105 the said section 74 in upright alinement with the section 73. Mounted to swing on the upper section 74 of the standard is a wire 79 for engaging against the inner side of the music sheets above the wire 69. As here 110 shown this holding wire 79 has a cam end 80 extended through an opening in the upper end of the standard and is engaged by a plate spring 81 which yieldingly holds the wire 79 115 against the music sheets.

In the operation, assuming the several sheets of the music to be folded, the parts will be in the position indicated in Figs. 2, 5 and 6, the several arms 24 resting upon the highermost part of the incline 15 and the 120 lower arms 24 being slightly forward of the one next above, and so on, upward. The finger 27 of the arms 18 carrying the wires 19 will be engaged in the notch of the lowermost arm 24 while the fingers of the other arms 18 125 will be successively engaged in the notches of the other shifting or turning arms. The end of the plate 28 is permitted to move sufficiently downward to engage with the lowermost arm 24 at its front side but when the 130

pneumatic 48 is operated, the piston in the cylinder 44 will be moved and through the agency of the rack 42 will turn the pinion 35 so that the arm 36 will be operated in a rotary direction. As this arm 36 is moved, the cam 41 thereon, by engaging with the inwardly turned portion 33 of the shaft 29 will rock said shaft carrying the plate 28 upwardly a sufficient distance to free the lowermost arm 24 and by a continued movement of said arm 36 the said lowermost arm 24 will be moved to carry the sheet to the left-hand side of the device. As the first or lowermost arm 24 is moved outward the next one above it will move downward upon the incline 15 and as the arm 36 returns to normal position the finger 37 will turn downward against the resistance of the spring 39, permitting said finger to pass underneath the lowermost arm 24 and then will move upward through the elastic force of the spring to engage against the rear side of said lowermost arm. This operation will be repeated for each leaf of the music to be turned. When it is desired to return one or more leaves of the music to closed or normal position the pneumatic 64 is to be operated, which through the piston 58 will cause the rack 56 to turn the pinion 53, thus causing the returning arm 54 to rotate and move the several turning arms back to normal position.

It will be noted that the cylinders 44 and 59 are each made in separable sections; that is, each cylinder has a fixed head portion 82, while the remainder of the cylinder is removable therefrom. It is held in engagement with the fixed head portion 82 however, by means of a loop 83 having pivotal connection with the head 82 and engaging with the outer end of the main section of the cylinders; by this arrangement the cylinders may be readily separated for cleaning and for repairing the pistons.

Having thus described my invention I claim as new and desire to secure by Letters Patent:—

1. A music leaf turner comprising a post, leaf carrying arms mounted to rotate on said post, turning arms mounted to rotate on the post and having notches at the free ends, fingers extended downward from the free ends of the leaf-carrying arms and adapted to engage in said notches, an arm mounted to rotate on the post, a spring-yielding finger on said arm for engaging with the turning arms and a pneumatic for operating said arm carrying the finger.

2. A music leaf turner comprising a post, leaf carrying arms mounted to rotate on the post, having downwardly extended fingers at the free ends, turning arms mounted to rotate on the post, and having notches for receiving said fingers, an inclined wall upon which the turning arms are designed to rest when in nor-

mal position, and means for moving the turning arms one at a time from said incline. 65

3. A music leaf turner comprising a post, leaf-carrying arms mounted to rotate on the post and having downwardly extended fingers, turning arms mounted to rotate on the post and having notches for receiving said fingers, a shifting arm mounted to rotate on the post, a spring-yielding finger on said shifting arm for engaging with the turning arms and means for operating said finger-carrying arm for shifting the turning arms one at a time. 70 75

4. A music leaf turner comprising a post, a plurality of leaf-carrying arms mounted to rotate thereon and having downwardly extended fingers at the free ends, turning arms mounted to rotate on the post and having notches at the ends for receiving the said fingers, the said turning arms being normally one upon another, an inclined surface on 80 which said turning arms are designed to rest, a spring for holding the turning arms yieldingly downward, and means for shifting each turning arm independently and carrying its leaf-carrying arm. 85 90

5. A music leaf turner comprising a post, a plurality of leaf-carrying arms mounted to rotate on said post and having downwardly extended fingers, turning arms mounted to swing on the post and having notches for receiving said fingers, a wall formed in the arc of a circle and having an inclined upper surface upon which said turning arms are designed to rest, a spring for yieldingly holding the turning arms in connection with said inclined surface, a detent plate for the turning arms, a shifting arm, a finger on said shifting arm for engaging successively with the turning arms and means operated by said shifting arm for releasing the detent plate from the 100 turning arms, one at a time. 95 105

6. A music leaf turner comprising a post, a plurality of leaf turning arms mounted to rotate on said post, each of said arms having a downwardly extended finger, a turning 110 arm for each leaf turning arm and having a notch at its end for receiving the finger of its leaf turning arm, a wall formed in the arc of a circle and having an inclined top surface upon which the turning arms are designed to rest, a detent plate for holding the turning arms in normal position, a shifting arm mounted to swing on the post, a spring-yielding finger on said shifting arm for engaging successively with the turning arms, a 115 shaft on which the detent plate is mounted, an angular portion on said shaft and a lug on the shifting arm for engaging with said angular portion to raise the detent plate from engagement with the turning arms one at a 120 time. 125

7. A music leaf turner comprising a post, a plurality of leaf-carrying arms mounted to

- rotate on the post, downwardly extended fingers on the free ends of said arms, turning arms having rotary relation to the post and having notches for receiving said fingers, a shifting arm for the turning arms, a pinion on the post to which said shifting arm is attached, a rack engaging with said pinion, and a pneumatic for operating the said rack in one direction.
10. 8. A music leaf turner comprising a post, a plurality of leaf-carrying arms mounted to rotate on the post, downwardly extended fingers on said arms, turning arms mounted to rotate on the post and having notches for receiving said fingers, a shifting arm mounted to rotate on the post, a spring-yielding finger on said shifting arm for engaging with the turning arms one at a time, a wall formed in the arc of a circle and having an inclined upper surface on which the turning arms are designed to rest, a pinion to which said shifting arm is connected, a rack engaging the said pinion, a cylinder, a piston in the cylinder having connection with said rack and a pneumatic for moving the piston in one direction.
9. A music leaf turner comprising a post, a plurality of leaf-carrying arms mounted to rotate on the post, downwardly extended fingers on said arms, turning arms having rotary connection with the post, the said turning arms being provided with notches for receiving said fingers, a wall formed in the arc of a circle and having an inclined upper surface upon which the turning arms are designed to rest, a shifting arm having rotary connection with the post, a finger yieldingly mounted on said shifting arm and adapted for engagement with the turning arms one at a time, a detent for the turning arms, means carried by the shifting arm for releasing the detent plate from the turning arms one at a time, a pneumatic for operating the shifting arm, and a pneumatic for turning the turning arms and leaf-carrying arms to normal position.
10. 10. A music leaf turner comprising a post, a plurality of leaf-carrying arms mounted to rotate on said post, downwardly extended fingers on said arms, turning arms having rotary connection to the post and provided with notches for receiving said fingers, a wall formed in the arc of a circle and having an inclined upper surface upon which the turning arms are designed to rest, turning arms held yieldingly in connection with said inclined surface, a shifting arm mounted to rotate on the post, a spring-yielding finger carried by said shifting arm and adapted to engage with the turning arms one at a time, a pinion to which the shifting arm is connected, a rack engaging the said pinion, a cylinder, a piston in said cylinder having connection with said rack, a pneumatic, and a pipe connection between said pneumatic and said cylinder.
11. A music leaf turner comprising a post, a plurality of leaf-carrying fingers mounted to swing on said post, downwardly extended fingers on said arms, turning arms having rotary connection with the post and provided with notches for receiving said fingers, a shifting arm mounted to rotate on the post, a spring-yielding finger on said shifting arm for engaging with the turning arms, a pneumatic for moving said arm in one direction, a returning arm mounted to swing on the post, and a pneumatic for operating said returning arm.

In testimony whereof I have signed my name to this specification in the presence of two subscribing witnesses.
